DRYING APPARATUS

Milton E. Hanson, Haddonfield, N. J., assignor to
 B. F. Sturtevant Company, Boston, Mass.

Application February 2, 1940, Serial No. 316,899

7 Claims. (Cl. 34—48)

This invention relates to drying apparatus and relates more particularly to apparatus for drying web material such as paper, cloth, Cellophane and the like or for drying printing or coatings 5 on the surface of same.

An object of the invention is to provide an efficient dryer for web material.

Another object of the invention is to provide an efficient, compact dryer for web material.

10 The invention will now be described with reference to the drawings, of which:

Fig. 1 is a plan view looking downwardly, with portions in section and portions in dotted outline, of a dryer embodying this invention;

15 Fig. 2 is a side elevation, with portions in section and portions in dotted outline, of the dryer of Fig. 1;

Fig. 3 is a sectional view along the lines 3—3 of Fig. 1;

20 Fig. 4 is an enlarged sectional view along the lines 4—4 of Fig. 3, and

Fig. 5 is an enlarged view of one of the idler rolls used.

The embodiment of the dryer illustrated was 25 designed for the drying of 30" wide Cellophane sheet which before and during the drying is printed upon with ink. The sheet moves continuously and progressively through the dryer which contains three drying sections.

30 The dryer includes the three similar drying sections 10 separated by the partition sheets 11. As shown by Fig. 2, the sheet 12 to be dried, enters the lower, left hand end (facing Fig. 2, of the drawings) of the left-hand section 10, 35 passes on the idler rolls 13, over an arch having four straight sides with the two uppermost of the straight sides forming an inverted V at the center of the section. The partition 14 extends from the ceiling 15 of the dryer to the 40 apex of the said inverted V and divides the dryer section 10 into two heated air supply portions as will be explained.

The four banks 16 of nozzles 17 are placed above the rolls 13 and follow the outline of said arch, 45 and the uppermost banks 16 converge to meet the partitions 14 and form an inverted V over and closely adjacent to said first mentioned inverted V.

The extended surface heaters 18 extend from 50 the left-hand end 19 of the dryer section 10 and form the partition sheet 11 to the center partition 14 and forms inverted V's extending over and adjacent the inverted V's formed by the uppermost nozzle banks 16.

55 The two other drying sections 10 include the

same apparatus with the same layout as described in the foregoing. The sheet leaving the left-hand section 10 enters the lower left-hand end of the center section 10, and on leaving the center section, enters the lower left hand 5 end of the right-hand section 10. At the entrance of the three sections are the hot rolls 20, and in advance with respect to sheet movement are fountains and impression rolls (not shown) for printing the sheet in three stages. 10

The two propeller fans 21 are placed between the ceiling 15 and roof 22 of each dryer section 10, one being located over each of the extended surface heaters 18, and communicating through a circular aperture in the ceiling 15 with the 15 dryer interior. The fans draw in fresh outdoor air through the inlets 23, and draw in as recirculated air, the heated air after it passes through the nozzles and strikes the sheet 12, through the 20 passages 24, between the nozzle banks 16 and the 25 side walls 25. Exhaust air is vented to the atmosphere through the ventilators 26.

The steam humidifiers 27 are located adjacent the right-hand fans 21 in each dryer section 10 and serve to maintain the drying air at the 25 proper humidity so that the web or paper will not dry too fast, too much, or lose its natural water content which causes shrinking. As shown by Fig. 3, the steam enters the humidifiers 27 through the pipes 28, and escapes into the recirculating air through the openings 34 and the condensate leaves the heaters through the drain pipe 35. 30

The fans 21 are driven through the pulleys 30 and belts 31 by the electric motor 32 located 35 on the exterior of the dryer, each fan being separately driven as illustrated by Figs. 1 and 2.

The plates 33 extend between adjacent nozzles 17 to points adjacent the sheet 12 and perform the functions of scraping off the film of air 40 which tends to adhere to the sheet and leave the dryer with it; of providing turbulence in the air flow thus expediting the drying action, and of equalizing the drying effect of the air by 45 guiding it crosswise the sheet, all of which result in adding to the efficiency and compactness of the dryer by cutting down air and heat losses, and decreasing the number of nozzles which otherwise would be required.

The roof, side and end walls of the dryer are 50 insulated with all of the air treating equipment mounted completely within the insulated walls.

In operation, the sheet 12 is moved over the 55 rolls 13 through the dryer, steam is supplied to the heaters 18 and humidifiers 27 and the fans 55

21 are operated to force air through the heaters 18 and nozzles 17 onto the surface of the sheet. The plates 33 guide the air to the two edges of the sheet and it then passes as recirculated air, 5 through the passages 24, to the inlets of the fans. Fresh make-up air enters the air streams through the inlets 23 and equal volumes of air are exhausted through the ventilators 26.

The dryers described in the foregoing provide 10 considerable drying surface in a small area, together with efficient and relatively inexpensive heater and fan layout. While one dryer section alone could be used as a complete dryer, the multiple layout of equipment employed lends 15 itself advantageously to interconnected drying sections for the purpose of drying successive colors or coatings, each being dried before the other is added, as illustrated and described.

While one embodiment of the invention has 20 been described for the purpose of illustration, it should be understood that the invention is not limited to the exact apparatus and arrangement of apparatus illustrated, as changes therefrom may be made by those skilled in the art without 25 departure from the essence of the invention.

What is claimed is:

1. Drying apparatus comprising two banks of 30 drying nozzles arranged as legs of an inverted V, heater tubes arranged as legs of inverted V's alongside said banks, a pair of fans adjacent said tubes, a partition extending through the apices of 35 said V's for guiding the air from one of said fans through the nozzles of one of said banks and the air from the other of said fans through the nozzles of the other of said banks, and means for guiding a web to be dried in a substantially inverted V-shaped path parallel to said banks of nozzles.

2. Drying apparatus comprising two banks of 40 drying nozzles arranged as legs of an inverted V, heater tubes arranged as legs of inverted V's alongside said banks, a pair of propeller fans arranged to blow air downwardly upon said tubes adjacent said tubes, a partition extending through the apices of said V's for guiding the air from one of said fans through the nozzles of one of said banks and the air from the other of said fans through the nozzles of the other of said banks, and means for guiding a web to be dried in a substantially inverted V-shaped path parallel to said banks of nozzles.

3. Drying apparatus comprising two banks of 45 drying nozzles arranged as legs of an inverted V, heater tubes arranged as legs of inverted V's alongside said banks, means above the apices of said V's for moving air through said heater and said nozzles, and means for moving a web to be dried in a substantially inverted V-shaped path 50 parallel to said nozzles.

4. Drying apparatus comprising two banks of 55 drying nozzles arranged as legs of an inverted V, heater tubes arranged as legs of inverted V's alongside said banks, means above the apices of said V's for moving air through said heater and 60

said nozzles, means for moving a web to be dried in a substantially inverted V-shaped path parallel to said nozzles, and means extending through the apices of said V's for dividing the air from said first mentioned means into two streams. 5

5. Drying apparatus comprising a drying chamber, a fan chamber above said drying chamber and separated therefrom by a ceiling, a plurality of idler rolls arranged in a plurality of straight lines extending from the floor of said drying chamber, first upwardly and then downwardly to said floor in a substantially arch-shaped path, for guiding a moving web for drying, a plurality of banks of nozzles conforming in outline to that of said rolls, a partition extending from said ceiling through said nozzles and dividing same into two similar groups, heater tubes extending from said partition to opposite walls of said drying chamber and between said nozzles and said ceiling, said ceiling having an aperture on each side 20 of said partition, and a fan in said fan chamber for moving air through said aperture and through said tubes and nozzles onto the web to be dried. 15

6. Drying apparatus comprising a drying chamber, a fan chamber above said drying chamber 25 and separated therefrom by a ceiling, a plurality of idler rolls arranged in a plurality of straight lines extending from the floor of said drying chamber, first upwardly and then downwardly to said floor in a substantially arch-shaped path, for 30 guiding a moving web for drying, a plurality of banks of nozzles conforming in outline to that of said rolls, a partition extending from said ceiling through said nozzles and dividing same into two similar groups, heater tubes extending from said 35 partition to opposite walls of said drying chamber and between said nozzles and said ceiling, said ceiling having an aperture on each side of said partition, propeller fans in said fan chamber in axial alignment with said apertures for moving 40 air through said apertures and through said tubes and nozzles onto the web to be dried.

7. Drying apparatus comprising a drying chamber, a fan chamber above said drying chamber and separated therefrom by a ceiling, a plurality 45 of idler rolls arranged in a plurality of straight lines extending from the floor of said drying chamber, first upwardly and then downwardly to said floor in a substantially arch-shaped path having upper center in the form of an inverted V, 50 for guiding a moving web for drying, a plurality of banks of nozzles conforming in outline to that of said rolls, a partition extending from said ceiling through said nozzles and dividing same into two similar groups, heater tubes arranged as legs 55 of an inverted V, extending from said partition to opposite walls of said drying chamber and between said nozzles and said ceiling, said ceiling having an aperture on each side of said partition, propeller fans in said fan chamber in axial alignment with said apertures for moving air through 60 said apertures and through said tubes and nozzles onto the web to be dried.
